APPARATUS FOR DEFIBERING AND DEINKING PAPERS

Edward Henry Partington, Wembley, and William Henry Porritt, Chilcompton, near Bath, England

Application February 10, 1938, Serial No. 189,850
In Great Britain February 10, 1937

1 Claim. (Cl. 92—20)

The present invention concerns the treatment of materials such as paper, paper board, and the like fibrous products for the purpose of recovering therefrom, *inter alia*, the fibrous constituents in a form in which they may be reutilised for the manufacture of paper, paper board, etc., and has particular reference to an apparatus whereby the said fibrous constituents may be recovered from printed waste papers and paper boards, in a clean, ink-free condition and also free from the other materials associated therewith in the paper, paper board and the like.

The treatment of paper and paper board especially when these are printed, in order to obtain a clean pulp therefrom involves, broadly speaking, three separate considerations, firstly there must be a suitable pretreatment whereby the paper or paper board can be brought into condition suitable for further mechanical treatment whereby the material can be defibered. This initial treatment must also be such as to facilitate the separation of any ink and fillers from the paper and enable these to be removed by straightforward washing. The second consideration is the nature of the mechanical treatment to which the pretreated material is to be subjected. This mechanical treatment must be such as completely to defber the paper, while at the same time not destroying the individual fibers. The third consideration is the necessity of so treating the pulp that the ink initially associated with the surface of the fibers is completely dislodged thus rendering it possible to wash the same out of the pulp by a simple aqueous washing step.

Accordingly, in the preferred method of using the apparatus of the present invention the paper, paper board or the like is subjected to a steeping operation in a suitable steeping liquor, whereafter it is subjected to mechanical treatment adapted to separate the fibers one from the other, and from the associated materials such as fillers, ink, size, loading and the like, but without damaging the fiber or shortening the mean fiber length unduly, this separation being so effected that the associated materials may readily be removed from the fiber by a simple washing operation, the fiber being then cleaned by such a washing operation.

To this end the invention provides a machine whereby a suspension of paper is operated on to form a stream or streams so directed that sufficient friction is set up between the paper or like particles carried in the suspension to result in the separation of the individual fibers one from the other and from the associated materials.

The initial step in the operation of the apparatus of the present invention may comprise a soaking operation with which there may be suitably associated a treatment with reagents adapted to assist in softening the paper or if desired in the modification thereof. For example caustic alkali may be employed and this may be introduced at the commencement of the steeping operation or in the course thereof. The nature of the steeping operation may, for example, depend upon the character of the paper or paper board under treatment, and where this is old and has become modified due to the formation of oxy-celluloses, the treatment with caustic soda or other suitable reagents such as alkali and alkaline earth salts of weak acids may be delayed until a later stage of the steeping process. In some circumstances it may be found desirable to incorporate wetting agents in the steeping solution. Thus, for example, if the paper contains oxy-cellulose in substantial quantities due to ageing and/or is heavily printed, it is found that an initial aqueous steeping materially assists in loosening the print whereas if caustic soda is added at the outset, the fibers immediately in contact with the ink do not respond so readily to disintegration by the later steps. Thus in some instances it is advantageous if the treatment with caustic soda and like reagents is delayed to a later stage in the steeping operation.

The steeping step may if desired be carried out with heating for example to about 160–200° F. this being found to shorten the operation considerably.

The second stage of the preferred operation consists in subjecting the steeped material to mechanical disintegration and according to the present invention this mechanical disintegration is carried out in such a manner that the ultimate disintegration is effected not by the action of beating or moving members but by the internal friction or abrasive action set up by the motion of the material under treatment. To this fact may be ascribed the valuable result that the ink initially present on the surface of the fibers becomes detached and not beaten into the surface of the fiber rendering it difficult to wash the pulp clean after disintegration is completed.

In conducting this stage of the operation, therefore, an apparatus is used in which the soaked paper, paper board or the like is caused to move in suspension at a suitable concentration, for example 5 to 10% by weight and in such a way that at one or more points in the course of its movement the suspension is converted into a

stream which is caused so to interact in opposition with another portion of the suspension that a considerable abrasive or disintegrating action is set up between the fragments of paper, paper board and the like in the neighbourhood of the interaction. It is found in practice that actually complete defibering and de-inking is achieved above a certain minimum of agitation in the manner indicated.

The suspensions so treated may readily be defibered and de-inked in the manner indicated in an economic period of minutes, provided that the initial steeping operation is carried out correctly, and thereafter may be readily washed so as to provide a pulp which is substantially indistinguishable from the pulp from which the paper or paper board forming the raw material was originally made.

The invention will be described with reference to the attached drawing which illustrates an embodiment of my improved apparatus for disintegrating paper and the like.

In the drawing there is shown an embodiment of the invention which has been found in practice to work satisfactorily and to permit of repeated batch handling without trouble. In this device a cylindrical barrel *a* is provided with a lateral inlet *b* for the suspension and an outlet *c* returning the treated pulp to a container *d* in such manner that the whole of the batch contained in the apparatus circulates uniformly through the barrel. For this purpose the container *d* is provided with a central sleeve *h* arranged as shown and the inflowing suspension circulating around it flows into the sleeve at the upper end. Within the barrel driven on a common shaft *e* are provided two propellers *f* and *g*. One of these, *f*, is arranged at a carefully selected point at the junction of the lateral inlet and the barrel while the second, *g*, is displaced towards the outlet of the barrel. Regarding the position of the first mentioned propeller *f*, this is arranged so that the plane containing the trailing edges of its blades (which will normally be substantially rectilinear) passes, at least when the propeller has normal dimensions (two bladed propellers being satisfactory) through the axis of the barrel at a point slightly removed in the direction of flow through the barrel from the point at which the axis of the feed inlet intersects the axis of the barrel (assuming the simple case where axes are concurrent). In general this displacement will be approximately $\frac{1}{8}$ th of an inch, this figure having surprisingly been found to be substantially independent of the size of the barrel, there being no noticeable variation required between the displacement for a barrel 1 inch in diameter and that for a barrel 15" in diameter with propellers in proportion. The effect of this first-mentioned propeller is apparently to produce by centrifugal effect a stream of the suspension into the inlet which consequently opposes the flow of material into the barrel. Thus while this first-mentioned propeller has some tendency to feed the material through the barrel due to its position in the inlet, it will not cause efficient circulation of the material. Consequently the second-mentioned propeller *g* is provided in order to secure a satisfactory flow through the apparatus consistent with the maintenance of the opposing streams in the inlet to the barrel. The ratio between the pitch of the propellers and also the absolute pitch of the propellers must be carefully controlled in relation to the speed at which the propellers are driven. Thus in the first place a certain degree

of friction between the suspended fragments must be attained to cause satisfactory disintegration of the paper and consequently there is a minimum speed of rotation of the first-mentioned propeller *f*. At the same time this degree of friction is only set up if there is a sufficient flow into the barrel. On the other hand if due to the second-mentioned propeller *g* the flow is rendered too great the centrifugal stream from the first-mentioned propeller *f* into the inlet may be partly or entirely suppressed with the consequent result that no defibering of a satisfactory character occurs.

In a particular case the barrel had an internal diameter of 4". The first-mentioned propeller *f* had a pitch of $7\frac{1}{2}$ ths inches and the second *g* a pitch of $7\frac{1}{2}$ inches, being otherwise similar to the first both being two bladed. To secure a sufficient freedom from direct interaction of one propeller on the other they are spaced some distance apart. In the apparatus in question a distance of $9\frac{1}{2}$ inches between the propellers is satisfactory and it was found that results did not improve if this distance was increased while if the propellers were noticeably closer the results deteriorated accordingly.

With the dimensions given above the optimum effect for defibering and de-inking of waste paper was found at a speed of revolution of the propellers of 2665 R. P. M. If this speed is not attained then the friction in the inlet requisite to secure adequate defibering is apparently lacking. If the speed is exceeded materially there is apparently a tendency for the second-mentioned propeller to suppress the centrifugal stream from the first-mentioned propeller with the result that efficiency again falls off. It is found that the ratios above suggested, the general dimensions and the speed of rotation of the propellers does not alter materially with increase in the size of the plant but it is particularly important however that the displacement of the first-mentioned propeller in the inlet conforms substantially with the figures given above.

It is however to be noted that these figures have been determined with relation to a cylindrical inlet and a cylindrical barrel of substantially the same diameter, the axes of the barrel and inlet being concurrent. If the form of the barrel varies in cross section and/or if the form of the inlet varies in cross section or if the ratio between the diameters of the barrel and inlet vary, or their axes are not concurrent, then the proportions and values given above may require modification which is best determined by experiment. The principle however should be to create in the inlet a sufficiently vigorous interaction of opposing streams of suspension to effect disintegration.

In all cases care must be taken to avoid beating of the pulp by mechanical members as far as possible since this, apart from breaking up the fiber, has also a tendency to beat the ink particles into the fiber rather than to loosen said particles from the fiber. This is shown clearly by the fact that if the machine is operated for too long a period upon a given batch of material it becomes impossible wholly to cleanse the material from ink by washing.

It may be mentioned that the washing out of the ink from defibered pulp made from printed raw materials is considerably facilitated by the presence of the fillers and loading materials in the raw materials. Thus where it is desired for example to treat printed papers which con-

tain little or no loading such as newsprint it is advantageous to use a suspension of fine material such as china clay to assist in the washing out of the ink.

A further useful application of the apparatus of the invention is in the production of particular varieties of cellulose from raw material of mixed character. Such particular varieties of cellulose are required for certain specific purposes, for example, in the manufacture of explosives. It is found that by suitable modification of the conditions of steeping and the solution used therefor and of the conditions of treatment during the defibering operation, effective separation of the constituents of the raw material cellulose can be achieved. For example stronger caustic soda may be used to effect at least a partial separation of the varieties of cellulose which may be present.

We claim:

In an apparatus for defibering and de-inking aqueous suspensions of steeped and partially disintegrated fibrous materials of the character of paper, the combination of a reservoir adapted to hold a substantial body of said suspension, a cyclic channel originating in said reservoir at a point below the normal liquid level in said

reservoir and at its other end returning to said reservoir, said channel comprising a relatively straight barrel section disposed at a level lower than said reservoir and an inlet section arranged to intersect with said barrel section at a relatively sharp angle, a propeller mounted in said channel in the zone formed by the intersection of said barrel section and said inlet section with its axis of rotation parallel to the axis of said barrel section whereby the centrifugal action of said propeller upon liquid surrounding it when it is rapidly rotated is directed at least in part through said inlet section in a direction away from the barrel section, means for rapidly rotating said propeller, a second propeller mounted in said relatively straight barrel section with its axis of rotation parallel to the axis of said barrel said second mentioned propeller being positioned at a substantial distance axially from the first mentioned propeller, and means for rapidly rotating said second mentioned propeller in a direction tending to force liquid through said barrel section away from the zone of intersection with said inlet section.
